LEWIS B. DOMAN, OF EAST SYRACUSE, NEW YORK.

ENGINE-CONTROLLED PNEUMATICALLY-OPERATED CIRCUIT CONTROLLER.

Application filed March 4, 1922. Serial No. 541,116.

This invention relates to an engine controlled pneumatically operated circuit controller for internal combustion engines in which the opening and closing of the ignition or other circuit is dependent upon varying air pressures produced by the action or inaction of the engine pistons.

The main object is to automatically cause the breaking of the circuit when the engine is at rest and thereby to avoid possible leakage of the current and running down of the battery in case the usual hand operated switch should be inadvertently left closed when the machine is at rest.

Another object is to enable the same device to be automatically operated by the starting of the engine to close the circuit in the event that the usual hand-switch is still closed.

A further object is to provide the pneumatic device with a secret air port, the position of which is known only to the operator and when open prevents the operation of the pneumatic device by the starting of the engine, thereby reducing the liability of theft of the machine but which port may be closed by the finger of the authorized user to allow the increased air-tension produced by the engine to operate the pneumatic device for closing the circuit.

Other objects and uses relating to specific parts of the device will be brought out in the following description:

In the drawings:

Figure 1 is a plan of a pneumatically operated circuit controller embodying the essential features of my invention ready for installation upon any portion of a car.

Figure 2 is a longitudinal sectional view of the same showing its connections with the intake manifold of an internal combustion engine and also its connections with the air port.

As illustrated, this device comprises a housing —1— of wood or any other suitable material having a chamber —2— in which is securely mounted a pneumatic device —3— preferably of the bellows type although it is evident that many other forms of pneumatics may be used if desired.

A tubular nipple —4— is secured in one side of the housing —1— to communicate with the interior of the pneumatic device —3— and preferably extends beyond the outer wall of the housing for attachment to a flexible pipe —5— which in turn is at-

tached to a tubular nipple —6— secured to and communicating with the interior of the intake manifold —A— of an internal combustion engine not shown, thereby placing 60 the pneumatic device —3— under the direct influence of the varying pressures in said manifold.

In other words, this connection between the pneumatic —3— and intake manifold 65 —A— enables the movable side as —3'— of the pneumatic device to be collapsed or closed by the suction produced in the intake manifold by the action of the engine pistons when the engine is in operation and 70 also permits the entrance of atmospheric air from said manifold into the pneumatic device to distend the same when the engine is at rest at which time, the atmospheric air will be admitted to the intake manifold 75 through the air intake of the carburetor in a manner well known to those skilled in this art.

A movable switch member —7— is secured to the movable side —3'— of the pneumatic 80 device —3— to move therewith into and out of contact with a cooperative terminal —8—, which is secured to the inner wall of the housing —1— within the chamber —2— in the path of movement of the contact end of 85 the terminal —7—, the latter being also enclosed within the chamber —2—.

These terminals —7— and —8— are connected by wires —9— and —10— to an ignition or other electric circuit —11— to which 90 current may be supplied by a battery —B—, said circuit being provided with the usual hand-switch —12— for opening and closing the same at will.

An air tube —13— is tightly fitted in registering openings in the housing —1— and stationary wall of the pneumatic device —3— to communicate with the interior of said pneumatic device and is connected by a flexible pipe —14— to a tubular extension 95 —15— having an air port —16— communicating with the atmosphere whereby atmospheric air may be admitted to the interior of the pneumatic device for inflating the same and thereby preventing the operation 100 of said pneumatic device to close the contacts —7— and —8— by the suction in the intake manifold —A— when the air port —16— is open, while on the other hand by placing the finger over the port —16— to 105 cut off the supply of atmospheric air to the interior of the pneumatic device —3— will

allow the suction produced in the intake manifold —A— to collapse said pneumatic device and thereby close the contacts —7— and —8— and ignition circuit —11— for 5 energizing the spark terminals as —a— when the hand-switch —12— is closed.

The tube —13— extends a short distance into the interior of the pneumatic device —3— to form a valve seat —17— for 10 operation with a valve —18— on the movable side —3'— of said pneumatic device to close communication between the air port —16— and interior of the pneumatic device when the engine is in operation and thereby 15 to close the contacts —7— and —8— of the pneumatically operated switch.

The flexible tubes —5— and —14— may 20 be of any length to permit the housing —1— and air port —16— to be placed on the car in different positions relatively to each other and to the manifold —A— as may be required for different makes of cars or to suit the convenience of the user.

25 Operation.

Assuming that the hand-switch —12— has 30 been closed as usual preceding the operation of the starting motor at which time, the pneumatic device —3— will be distended by atmospheric air admitted thereto either from the intake manifold —A— or from the atmospheric port —16—. Then by operating the starting motor to start the engine and placing the finger over the atmospheric port 35 —16— will cause a sufficient suction or tension in the manifold and pneumatic device —3— to collapse the movable side of said pneumatic device and close the contacts —7— and —8— until the motor is running 40 under its own power, the valve —18— being simultaneously closed against its seat —17— to cut off communication between the interior of the pneumatic device and atmospheric port —16— whereupon the finger 45 may be removed from the port —16— while the suction produced by the engine in the manifold —A— and pneumatic device —3— causes said pneumatic device with the valve —18— and terminal —7— thereon to remain in their closed positions as long as the 50 engine is in operation.

If, however, the engine should be stopped and the hand-switch —12— should be inadvertently closed, atmospheric air would be 55 instantly admitted to the interior of the pneumatic —3— either through the manifold —A— or through the atmospheric port —16— to distend the same and thereby open the terminal —7— to break the ignition circuit and prevent discharge of the battery.

The port —16— may be placed in some secret position known only to the operator or authorized user of the car and it therefore, follows that when the engine is at rest, 60 it would be practically impossible to start

the same to run under its own power even though it might be operated by the starting motor. It could not be operated under its own power because of the distention of the pneumatic and consequent breaking of the 70 ignition circuit by the opening of the terminal —7— due to the admission of atmospheric air to the interior of the pneumatic device to neutralize the suction effect produced by the action of the engine pistons, 75 thereby reducing the liability of theft of the car in addition to conserving the energy of the battery.

It is evident however, that when the authorized operator wishes to start the car 80 under its own power, it is simply necessary to close the atmospheric port —16— by the finger or other suitable closure thereby cutting off the entrance of atmospheric air to the pneumatic device and permitting the suction of the engine to exert its full force upon 85 said pneumatic device to collapse the same and thereby to close the ignition circuit through the closing of the terminals —7— and —8—, it being understood that the 90 starting motor is operated simultaneously with the closing of the port —16—.

It is obvious, however, that the atmospheric port —16— and its connection with the interior of the pneumatic device —3— 95 together with the valve —18— may be dispensed with without destroying the major function of the device in controlling the ignition circuit through the medium of the pneumatic device as affected by the variations 100 of air tension in the manifold —A— and that other changes may be made in the detail construction and arrangement of the various parts without departing from the spirit of the invention.

It will be noted that the passage leading from the pneumatic device —3— to the intake manifold —A— is restricted at —4'— to a diameter appreciably less than that of the passage leading from the same pneumatic device to the air port —16—, the object of which is to retard the collapse of the pneumatic device and consequent closing of the switch under the air tension in the intake manifold until the atmosphere 115 port —16— is closed by the finger or other stoppage, which is only for a short duration or until the valve —18— has closed the port —17— after which the air intake port —16— may be opened with the assurance 120 that the supply of atmospheric air to the pneumatic device —3— will be cut off by the valve —18— and the switch closed as long as the engine is in operation.

What I claim is:

1. A circuit controller for internal combustion engines, comprising an electric switch, a pneumatically-operated device having a suction passage for communication with the intake manifold of the engine and another 130

- passage for communication with the atmosphere, the atmosphere passage being adapted to be closed at will to cause said device to be operated by suction in the first-named passage to close the switch, and means actuated by said pneumatic device for closing said atmosphere passage. 2. A pneumatic circuit-controller for internal combustion engines as in claim 1, in which the first-named passage is of less capacity than the atmosphere passage. 3. A circuit controller for internal combustion engines comprising a normally open circuit-closer, a pneumatically-operated device adapted to be actuated by suction of the engine to close the circuit-closer and provided with a normally open atmosphere passage normally preventing the operation of the pneumatic device by said suction, said atmosphere passage being adapted to be closed at will to cause said operation, and means actuated by said pneumatic device for closing said atmosphere passage. 4. A circuit controller for internal combustion engines comprising a normally open electric switch, a switch-operating pneumatic device connected by a restricted passage with the intake manifold of the engine and provided with a normally open atmosphere passage adapted to be closed at will to permit the operation of said pneumatic device to close the switch, and a valve actuated by said pneumatic device for closing the atmosphere passage when the switch is closed. 5. A pneumatically operated circuit controller for internal combustion engines having an intake manifold, comprising an electric switch, means adapted to be made responsive to varying pressures in the intake manifold for operating the switch, said switch-operating means having a passage normally open to the atmosphere for opening the switch and adapted to be closed by the operator to close the switch, and means actuated by the switch-operating means for closing said atmosphere passage and keeping it closed while the engine is in action.

In witness whereof I have hereunto set my hand this 21st day of February, 1922.

LEWIS B. DOMAN.
